G. A. Parker

UNITED STATES PATENT OFFICE.

GEORGE A. PARKER, OF LANCASTER, MASSACHUSETTS.

IMPROVED MODE OF CONSTRUCTION OF PIERS, &c.

Specification forming part of Letters Patent No. 41,935, dated March 15, 1864.

To all whom it may concern:

Be it known that I, GEORGE A. PARKER, of the town of Lancaster, in the county of Worcester and State of Massachusetts, have invented a new and Improved Mode or Process of Subaqueous Construction, which I have denominated "A Portable Constructing-Pier," and which is designed to be used in submerging, founding, and erecting subaqueous structures in localities where piles cannot be driven, and which can likewise serve as a wharf or pier for temporary or permanent use where piles cannot be driven, or where stone-work would be too expensive, difficult, or impracticable; and I do hereby declare that the following is a full, clear, and exact description thereof, reference being had to the accompanying drawings, and to the letters of reference marked thereon.

Figure 1 is a side view of my invention in connection with a section of a caisson placed on a suspended platform in position for lowering to the foundation of the proposed structure. Fig. 2 is an end view of my invention in connection with a finished bridge-pier. Fig. 3 is a plan of my invention in connection with a plan of one-half of a finished bridge-pier with the coping removed. Fig. 4 is an elevation on a larger scale of a single section of my invention, and shows in detail the composition of one of a series of hollow cylindrical columns.

Similar letters in the several figures indicate corresponding parts.

To enable others skilled in the art to make and use my invention, I will describe its construction and mode of operation.

In the accompanying drawings, A represents an uneven rocky bottom. B B' B² B³ represent the several courses of a timber platform. C C' C² C³ represent the several sections of a caisson. D represents the coping-course of stone. E represents the stone-work. F represents the lowering machinery of a bridge-pier. G represents a hollow cylindrical column. H represents a male screw fitting into a nut within the column G at its lower extremity. K represents a wrench whereby to turn the screw H. L represents tension-rods fastened by lugs M to the column G, and connected by swivels N. O represents a stay-bar uniting the cylindrical columns, to which it is fastened by screw-bolts P. Q represents tie-beams, which connect said col-

umns together at the top. R represents the floor-timbers. S represents adjustable connecting-rods that bind together two portable constructing-piers.

In constructing bridge-piers or other subaqueous structures on a rocky bottom where the caisson is used, or where the solid pier is to be lowered, the mode of operating with my invention is as follows:

Two portable piers are employed—one on each side of the proposed structure—and fastened together, as shown in the drawings. Each of said piers is put together on a float at or near its proposed position for use. Said piers may be built in sections and fastened together under water by divers; or they may be completely put together and made rigid upon a float at the side of the proposed structure. These piers may be lowered to the bottom by several modes—first, by suspending each of them, by means of a windlass, on a gallows-frame resting upon two floats, one on each side of said pier. When the lowering apparatus shall have been thus prepared, the said pier should be elevated sufficiently to allow the withdrawal of the float whereon it was built, and it then may be lowered to the bottom by means of the windlass. The corresponding pier should be lowered in like manner, and each pier should then be floored over. Afterward the screws H should be turned upward or downward, as may be required, by the wrench K, or equivalent means, until the floored surface of each pier shall become level, and the pier will be held in its place by forcing the screws into the bed of the stream in holes previously drilled for that purpose, or otherwise, after which both of said piers should be fastened together, as shown in the drawings.

The second process of sinking said piers is as follows: On each side of the proposed structure a float is stationed, and pieces of timber or other supports laid across from one float to the other, upon which the lowest section of said pier is put together, and afterward raised by means of a windlass, as before described, sufficiently high to permit the withdrawal of the supports, and then lowered to such a degree that its upper part shall extend a short distance above the surface of the water, in which position it should be sustained and held by supports laid across from one float to the other and passing under the upper

course of stay-bars. Another section of the pier is built upon the lowest, and the same mode of sinking is repeated. A similar process of building and lowering the several sections of the pier is carried out until the pier shall be sunk on the bottom in a complete state. Additional supports may be introduced if the superincumbent weight should render them necessary.

The third process of lowering said piers is as follows: The pier should be built on a float in the manner hereinbefore described, and then lowered from a gallows-frame somewhat higher than the top of the pier, and resting on floats, one on each side of the pier, by means of screws turning in nuts fastened to said piers by pieces of timber or other suitable means.

The fourth process of lowering said piers consists in suspending each pier from a pile-driver adapted to the purpose, and lowering it into position by blocks and falls, windlass, or other machinery.

The fifth process of lowering the constructing-pier is as follows: An ordinary stone-boat of suitable capacity is used. In its center is placed a series of derricks with a boom of sufficient length to extend beyond the side of the proposed structure to the distance of half the width of the constructing-pier, with a capacity in each derrick of raising and sustaining four or five tons. The derricks are such as are commonly used in stone-boats employed in bridge-construction.

The stone-boat thus equipped is moved in a proper position by the side of the proposed structure, and opposite to it is stationed a float, whose deck or upper surface is level with the deck of the stone-boat, from which it is separated by a distance equal to the width of the proposed structure. Pieces of timber or other supports extend from the deck of the stone-boat to the float, of sufficient strength and number to sustain the constructing-pier while in process of building or being put together. The first section of the constructing-pier is put together upon these supports and then attached to the derricks, and raised sufficiently high to permit the removal of their supports, and then lowered, so as to allow the insertion of the same supports beneath the upper line of stay-bars, so that the section may be held suspended by means of these supports.

The second section of the constructing-pier is built upon the first in the mode before described, and when completed its supports are removed, the section is attached to the derricks, and lowered to the requisite distance, where it is held suspended by supports inserted as before described.

Additional sections are built, attached to the derricks, lowered, and held in position in like manner until the constructing-pier is finished and rests upon the bottom of the stream, when it is adjusted to a level position by means of the screws H.

In case the invention is designed for permanent use as a wharf or pier, it may be necessary to drill holes in the rock for the insertion of the screws to hold the structure firmly in place, which holes can be made by divers or by long drills worked from the surface of the water.

In case it be intended to use said pier as an independent structure, either one of the processes before described may be employed to sink it.

Before operating with my invention as a means for submerging, founding, and erecting subaqueous structures it is necessary to prepare a foundation at the bed of the water by smoothing it off by the aid of divers, by blasting or other submarine process, or by introducing a layer of concrete or other suitable material.

Afterward, in the case of bridge-piers or similar fabrics, the timber platform B B' B² B³ should be floated into place between two of the portable constructing-piers, which should thereupon be fastened together in the manner shown in the drawings, or by equivalent justed and fixed in connection with the supports, and the lowering-screws should be appended platform, as shown in the drawings.

The lowest section of a caisson, C, is securely placed upon the platform and built in with masonry. The screws are then turned, and the structure is lowered to such a distance that its top projects a little above the surface of the water. Another section, C', should be superimposed on the first and the intervening joint be made water-tight. In this second section of the caisson masonry should be laid, as before described, and the same process of lowering should be repeated. Additional sections of the caissons should be similarly used to the extent required by the depth of water, and the same process of building in masonry and lowering the fabric should be repeated until the structure shall rest upon its proper foundations and extend to a sufficient elevation above the surface of the water.

When the structure resting on its foundation shall project above the surface of the water, the portable constructing-pier may be removed and used elsewhere for a similar purpose.

What I claim as my invention, and desire to secure by Letters Patent, is—

1. A portable constructing-pier supported upon and leveled or adjusted by or to the bed of the stream upon which it rests, substantially as and for the purpose described.
2. In combination with constructing-piers, either portable or permanent, the fastening of them to the bed of the stream by screws forced into the same from the top of the pier, substantially as described.
